Christian Nyhus, Inventor

By *Victor J. Evans* Attorney

UNITED STATES PATENT OFFICE.

CHRISTIAN NYHUS, OF VILLISCA, IOWA.

GARMENT-FASTENER.

SPECIFICATION forming part of Letters Patent No. 679,394, dated July 30, 1901.

Application filed June 25, 1900. Serial No. 21,534. (No model.)

To all whom it may concern:

Be it known that I, CHRISTIAN NYHUS, a citizen of the United States, residing at Villisca, in the county of Montgomery and State 5 of Iowa, have invented new and useful Improvements in Garment-Fasteners, of which the following is a specification.

This invention relates to new and useful improvements in garment-fasteners; and its 10 primary object is to provide a simple and durable device which may be readily secured to garments without necessitating the use of thread.

To this end the invention consists in providing a loop portion and a hook portion, each 15 of which is provided with recurved half-spear-head prongs, which may be readily inserted through the fabric and the shoulders of which will prevent the withdrawal thereof.

The invention also consists in the further 20 novel construction and combination of parts, which will be hereinafter more fully described and claimed, and illustrated in the accompanying drawings, showing the preferred form 25 of my invention, and in which—

Figure 1 is a perspective view showing the device in use. Fig. 2 is a side elevation of the parts of the fastener in engagement with each other, said parts being shown secured to the 30 fabric. Fig. 3 is a detail view of the loop portion of the fastener. Fig. 4 is a similar view of the hook portion. Figs. 5 and 6 are detail views of the loop-blank and hoop-blank before bent into proper shape.

In the drawings the same reference characters indicate the same parts of the invention.

1 is a cross-strip of the loop portion, formed 35 of any suitable material and having parallel arms or prongs 2 extending therefrom in the form of half spear-heads, leaving a rectangular opening 2^a. The outer edges of these prongs are inclined outwardly from the ends thereof and are recessed at points adjacent to the strip 1, forming shoulders 3 and trans- 45 verse openings 3^a, as shown.

The hook portion of the fastener is formed 50 from a blank of suitable material and comprises a tongue 4, which extends from one end of a substantially rectangular plate 5, leaving outer shoulders 5^a. Upon the opposite end 55 of this plate, at the sides thereof, extend parallel arms 6, the outer edge of each of which

is inclined outwardly from the end thereof and is recessed near the plate 5, forming a shoulder 7 and transverse opening 7^a, the 55 arms 6 leaving a rectangular opening 6^a between them. The hook portion is formed by bending the tongue 4 upon itself and to one side of the plate 5, and the arms 6 are also bent upon themselves at the opposite side of 60 said plate, so that this member of the fastener will appear as shown in Fig. 4.

The loop portion of the fastener is formed by simply bending the arms 2 upon themselves and over the strip 1, as shown in Fig. 3. This 65 loop portion is secured to one of the parts of the garment, to be fastened together by inserting the prongs through the fabric, as shown in Figs. 1 and 2. The hook portion is inserted in a similar manner in the remaining 70 section of the garment, and the tongue 4 may then be readily placed in engagement with the cross-strip 1, as is obvious.

It will be seen that after the arms 2 and 6 have once been inserted into the fabric it will 75 be difficult to remove the same, as the shoulders 7 thereof will engage with the fabric after passing therethrough.

From the foregoing description, taken in connection with the accompanying drawings, 80 the construction and advantages of my improved garment-fastener will be readily apparent without requiring an extended explanation. It will be seen that the device is simple of construction, that said construction 85 permits of its manufacture at small cost, and that it is exceedingly well adapted for the purpose for which it is designed, and it will of course be understood that various changes in the form, proportion, and the minor details 90 of construction may be resorted to without departing from the spirit or sacrificing any of the advantages thereof.

Having thus described the invention, what is claimed, and desired to be secured by Letters Patent, is—

A garment-fastener comprising a loop part 100 constructed with a plain cross-strip having a pair of prongs of acute shape formed with recesses providing shoulders and reduced parts 105 bent at right angles to the cross-strip and to the prongs, so as to bring the latter in rear of and across the cross-strip between the ends of the latter, and a hook part constructed with

a rectangular body having a pair of prongs of acute angle shape at one end formed with recesses providing shoulders and narrow parts bent at right angles to the body and to the prongs so as to bring the latter in front of the body parallel therewith, and a reduced part providing shoulders at the other end of the body and a tongue projecting partly in

the plane of the body and returned in rear of the latter to provide a hook.

In testimony whereof I affix my signature in presence of two witnesses.

CHRISTIAN NYHUS.
